DESIGN FOR A TOILET KIT

Norman R. Worley, White City, Kans.

Application January 10, 1946, Serial No. 125,435

Term of patent 7 years

(CL. D86—10)

To all whom it may concern:

Be it known that I, Norman R. Worley, a citizen of the United States, residing at White City, in the county of Morris and State of Kansas, have invented a new, original, and ornamental Design for a Toilet Kit, of which the following is a specification, reference being had to the accompanying drawing, forming part thereof, in which

Fig. 1 is a perspective view of a toilet kit embodying my new design with the lid closed, and

Fig. 2 is a perspective view of the toilet kit shown in Fig. 1 with the lid open.

I claim:

The ornamental design for a toilet kit, substantially as shown.

NORMAN R. WORLEY.
